(57) **CLAIM**

The ornamental design for a fighting D-pad arcade, as shown and described.

DESCRIPTION

FIG. 1 is a top front perspective view of a fighting D-pad arcade showing my new design;

FIG. 2 is a bottom rear perspective view thereof;

FIG. 3 is a front elevational view thereof;

FIG. 4 is a back elevational view thereof;

FIG. 5 is a top plan view thereof;

FIG. 6 is a bottom plan view thereof;

FIG. 7 is a left elevational view thereof;

FIG. 8 is a right elevational view thereof;

FIG. 9 is a top front perspective view thereof;

FIG. 10 is a front elevational view thereof; and,

FIG. 11 is a top plan view thereof.

The broken line showing the back panel and angled grip is included for the purpose of illustrating environmental structure and forms no part of the claimed design.
